RAIL FASTENING DEVICE

Hans Hodel, Engelberg, Switzerland

Application December 27, 1954, Serial No. 477,683

Claims priority, application Switzerland January 7, 1954

6 Claims. (Cl. 238—349)

Elastic rail spikes of various types for fixing rails to sleepers have been known and used in railway permanent way construction for a long time. They have proved their worth in practice and this is also the reason why they are being used to an ever greater degree.

The present invention is concerned with a particular type of such elastic spikes; it consists essentially in that the elastic arm of the spike extends along the rail foot in such manner that—when seen in the plan view—it engages only with its end portion over the said rail foot and is thereby subjected to torsional stress.

Further features of the invention will be evident from the claims, the specification and the drawings, wherein several constructional forms of the rail fastening device according to the invention are illustrated purely by way of example. In the drawings:

Fig. 1 is a side view of a first constructional form;
Fig. 2 is a front view according to Fig. 1;
Fig. 3 is a plan view according to Fig. 1;
Fig. 4 is a plan view of a second constructional form;
Fig. 5 is a plan view of a third constructional form,
and

Fig. 6 is a side view of a portion of a modified spike.
According to the constructional example shown in Figs. 1-3, the elastic spike consists of a driven-in pin portion 1 of an elastic arm 3 connected thereto, the said arm 3 being bent over at the point 2 and having its free end designated as 6. The elastic spike can consist of a bent rolled bar of any desired cross-sectional form, advantageously of round cross-sectional form. In order to fix the rail 4 to the support or sleeper 5, an elastic spike is driven into the sleeper 5 in the manner shown in the drawing, the end 6 of the elastic arm 3 pressing the foot 4b of the rail 4 downwards on to the support or sleeper 5.

Seen in plan view as shown in Fig. 3, the elastic arm 3 extends along the rail foot in such manner that it engages only with its short end 6 over the said rail foot and is subjected to torsional and bending stresses practically over its entire length. A further bend 7 brings the elastic arm 3 to merge into the relatively short end portion 6, which presses the rail foot 4 on to the support 5.

According to the constructional example as in Fig. 4, the elastic arm 3, 6 can also extend in an arc from the point at which the arm end 6 contacts the rail foot 4, so that the elastic arm 3 is subjected to a higher degree of torsional stressing than the elastic arm according to Figs. 1-3.

In order to obtain an even greater spring distance for the arm 3, the constructional form according to Fig. 3 is provided, wherein after the driven-in pin portion 1 the elastic arm 3 is first of all bent over in a curve and then merges into a further curve in the end portion 6.

In the case of the elastic torsion spikes illustrated in Figs. 1-5 other shapes of the elastic arm 3 are possible, for example the part 3 forming the transition from the driven-in pin portion 1 to the pressure part 6 can form

2

any desired angle relatively to the edge of the rail foot other than the angle *a* shown in Fig. 4.

As will be seen from Figures 3, 4 and 5, the spikes are so driven into the sleepers 5a that the driven-in pin portion 1 is driven into the edge zone 5c of the sleeper 5, and the elastic arm part 6 which engages over a short length over the rail foot 4 presses the rail on to the sleeper 5a substantially over the centre line 5b of the said sleeper. The result is thereby achieved that the rail is always 10 pressed centrally on to the sleeper. This has the advantage that the support of the rail on the sleeper corresponds rather to a rocker bearing, especially if an elastic interlayer is inserted between the rail foot 4 and the sleeper 5. From the permanent way constructional point 15 of view this arrangement has the advantage that the sleeper remains steadier in the ballast bed, that is: it rocks less than hitherto known arrangements and consequently exerts a more uniform stress on the ballast under the rail and thereby reduces the amount of rail maintenance necessary. The spike can be positioned between the rail 4 and the sleeper 5 with or without steel supports.

The elastic spike 1, 3, 6 described is of such construction and is so arranged that in order to release the rail 4 from the sleeper 5 the spike need only be partially drawn out and then swung away, when in this position, from the rail foot. Therefore the spike does not have to be completely drawn out of the sleeper in order to release the rail.

Instead of using a single spike in each case in accordance with the construction shown in Figs. 1 and 2, it is also possible to use two spikes in laterally inverted arrangement on one side of the rail foot 4, as shown in chain lines in Figs. 1, 3 and 4. In this case two laterally inverted single-pin elastic torsion spikes can be combined to form one single spike, the two single-pin spikes being connected rigidly to one another to form a two-pin elastic torsion spike by any desired means, e. g. by welding.

As will be seen from the arrangement of two laterally inverted spikes (Figs. 1, 3 and 4), they are secured by virtue of their construction and mutual arrangement against unintentional swinging out of the arms 3, thereby securing the fastening device.

The resistance against withdrawal of the elastic torsion spike may be increased, especially in the case of soft wood sleepers, by providing notches, Fig. 6, along the driven-in pin portion. These notches will be particularly effective if arranged in the manner of fish-scales pointing upwards so that, when being withdrawn, they will engage like barbs into the material of the timber sleepers, Fig. 6.

Said notches may also be arranged in a screw-thread-like manner at the circumference of the pin part. This has the advantage that—with the driven-in portion made of round rolled material—the elastic spike, on being turned, will automatically engage into the timber sleeper.

Hitherto known single-pin elastic spikes have the disadvantage that the elastic head is only subjected to bending stress and not to torsional stress, thus using the material in a very uneconomical manner. Moreover the known construction of elastic heads, which is subjected only to bending stress, has the disadvantage of having only slight elasticity, and therefore the nail must consist of two parts bearing on one another in order to obtain the elasticity necessary in practice. Experience also shows that the elastic heads of the known elastic spikes, even where they are of square cross-section, become turned out of position under the effect of train running and, therefore afford no security against rail creep.

Elastic spikes with two driven-in pin portions situated some distance from one another are also known. These have the disadvantage that they also exhibit little elasticity, and are subjected in the vicinity of the driven-in pin portions, as in the case of a fixed girder, to negative

bending moments which have a drawing-out effect and therefore readily loosen the spikes.

Moreover hitherto known elastic spikes have the disadvantage that, for example, when the rails are being replaced, the said spikes have to be withdrawn completely out of the sleeper, which requires considerable expenditure of energy. The elastic spikes according to the present invention is formed from a rolled bar having generally a round cross-section, which by its special construction or configuration and arrangement obviates the aforesaid disadvantages.

What I claim is:

1. A rail supporting and fastening means comprising a sleeper, and a resilient spike to contact a flange of the rail and driven into the sleeper, said spike having an integral spring arm and a sleeper-engaging portion at one end of the spike and at approximately right angles relative to the spring arm, said spike also having a flange engaging portion on the other end of the spike, said sleeper-engaging portion of the spike being anchored in the sleeper immediately adjacent said rail flange near the edge zone of the sleeper, and the spring arm of the spike by means of its flange engaging portion clampedly engaging said rail flange on the approximate longitudinal center line of the sleeper and the flange engaging portion being at approximately right angles to the spring arm of the spike.

2. A rail supporting and fastening means according to claim 1, in which the spring arm is disposed mainly adjacent the rail flange as viewed in a vertical direction on the rail.

3. A rail supporting and fastening means according to claim 1, in which the spring arm is in the shape of a bar and extends from said engaging portion in an arc with respect to a depressing end portion of the spike.

5
10

4. A rail supporting and fastening means according to claim 1, in which on one and the same side of the rail flange there are provided two resilient spikes, the sleeper-engaging portion of each spike being driven into a sleeper edge zone so that their depressing ends which are at right angles to the rail axis substantially contact each other so that the two spikes prevent each other from turning about the sleeper-engaging spike portions.

5. A rail supporting and fastening means according to claim 1, in which the spring arm is curved from said engaging portion in a direction opposite to the depressing end and subsequently in a further arc to the end portion which is directed at right angles towards the rail axis.

6. A rail supporting and fastening means comprising a sleeper, and a resilient spike to contact a flange of the rail and driven into the sleeper, said spike having an integral spring arm with a flange engaging portion on one end of the spike and extending at approximately right angles to the spring arm, said spike having a sleeper engaging pin to be embedded in the sleeper near one side edge zone thereof and the flange engaging portion with its free end engaging the flange at the approximate longitudinal axis of the sleeper.
